(57) **CLAIM**

The ornamental design for a tail light assembly, as shown and described.

DESCRIPTION

FIG. 1 is a front elevational view of a tail light assembly showing my design; and,

FIG. 2 is a rear elevational view thereof; and,

FIG. 3 is a right elevational view showing my new design; and,

FIG. 4 is a left elevational view thereof; and,
FIG. 5 is a top plan view thereof; and,

FIG. 6 is a bottom plan view of my new design; and,
FIG. 7 is a perspective view of my new design shown in an example environment of a motorcycle.

The dash lines showing the adjacent motorcycle is only for showing the surrounding environment and is not part of the claimed design.
